UNITED STATES PATENT OFFICE.

C. ALFRED JACOBSON, OF RENO, NEVADA.

COMPUTING-MACHINE.

1,149,143.

Specification of Letters Patent.

Patented Aug. 3, 1915.

Application filed February 10, 1915. Serial No. 7,323.

To all whom it may concern:

Be it known that I, C. ALFRED JACOBSON, a citizen of the United States, residing at Reno, in the county of Washoe and State of Nevada, have invented new and useful Improvements in Computing-Machines, of which the following is a specification.

My invention relates to a computing machine or mechanical calculator, and its object is to provide a simple, inexpensive and efficient construction of calculating machine which may be employed for general calculating purposes in a ready and convenient manner.

The invention consists of the features of construction, combination and arrangement of parts herein fully described and claimed, reference being had to the accompanying drawings in which:

20 Figure 1 is a front elevation of a computing machine or mechanical calculator embodying my invention. Fig. 2 is a vertical front to rear section thereof. Fig. 3 is a vertical transverse section. Fig. 4 is a plan 25 section of the side plates, drums and allied parts on an enlarged scale. Fig. 5 is a detail section on the line 5—5 of Fig. 4. Fig. 6 is a detail section on the line 6—6 of Fig. 4. Fig. 7 is a section through the casing 30 showing the sliding cover and guides therefor. Fig. 8 is a section through the sliding cover. Figs. 9 and 10 are plan views of the graduation sheets upon the upper and lower drums, portions being broken away.

35 In carrying my invention into practice, I provide a casing 1, supported in a downwardly and forwardly inclined position upon standards or uprights 2. This casing comprises side plates 3 mounted on the standards, a fixed wall 4, a bottom board 5, and a rolling top or cover 6, the plates and standards being connected and tied together in any strong and durable manner. The wall 4 extends from the rear edge of the 45 bottom board 5 to the upper front portion of the casing, and is preferably formed of a continuous series of steel strips 7 riveted or otherwise suitably fastened together and suitably fixed to the side plates 3. The bottom board 5 may be of either metal or wood, and is disposed above a laterally sliding shelf or lid 8, which may be drawn outward for use at one side of the machine to serve as a support for a book in making notations, etc. The top or cover 6 is likewise

composed of a series of steel strips 9 which are flexibly connected or hinged together, as shown at 10, and the side edges of this cover move in suitable guide grooves 11, formed in or upon the side plates 3. The forward strips 9 are attached to a bottom strip 11' of wood or other suitable material which is adapted to close down upon the bottom board 5 and to be locked thereto in any preferred manner. The casing thus 65 constructed is inclined at substantially an oblique angle to the horizontal and has its top correspondingly sloped for greater convenience in operating the working parts and consulting the computing or calculating devices, hereinafter described.

The computing or calculating devices consist of upper and lower drums 13 and 14, each comprising a cylindrical body 15 secured to central end disks 16 and 17, and a central and tubular hub 18 extending through the centers of said disks. The peripheral surfaces of the cylindrical bodies 15 of the drum bear suitable tables or calculating matter, and the hubs 18 of the drums are fitted to slide and rotate upon transverse shafts 19 and 20, revolvably mounted in suitable bearings 21 in the side plates 3. To one end of each drum is secured a hand wheel 22, whereby it may be revolved and slid along its carrier shaft, and to the ends of each of the carrier shafts 19 and 20 are attached hand wheels 23, whereby said shafts may be rotated. Stop collars 24 are provided on each shaft for 90 limiting the sliding motion of the drum in either direction, and for the purpose of fixing each drum against rotation on its carrier shaft a locking mechanism is provided which is constructed as follows. One end 95 of the tubular hub 18 of each drum is longitudinally slit to form a pair of diametrically disposed friction brake shoes 25, normally held by the resiliency of the spring metal of which the hub is formed from engagement with the associated carrier shaft, thereby allowing the drum to be freely rotated or slid longitudinally on said shaft. Arranged for engagement with each of these 100 brake shoes is a dog 26, pivotally mounted, as at 27, upon the adjacent end head 17 and having a curved or cam surface 28 at one end for engagement with the brake shoe. The other end of the dog is formed to provide a toothed segment 29 meshing with a 110

pinion 30 on a shaft 31 journaled upon the said head 17 and provided with a knurled knob or hand wheel 32, whereby it may be turned to oscillate the dog upon its pivotal axis. It will thus be evident that by turning the dog in one direction the curved or cam surface thereof will be moved into engagement with the brake shoe, thereby forcing said brake shoe into frictional engagement with the carrier shaft, while on a reverse movement of the dog the curved or cam face of said dog will be moved away from the brake shoe, allowing the latter to spring out of engagement with the carrier shaft. Hence each drum may be locked to its carrier shaft both against rotation and longitudinal sliding movement.

Upon the carrier shafts 19 and 20 adjacent to one of the side plates 3 are intermeshing spur gears 33 and 34, whereby the carrier shafts are adapted to be revolved to like degrees in unison, and meshing with the gear 33 is a pinion 35 carried by a shaft 36, provided with a knob or hand wheel 36, whereby said pinion may be operated to rotate the aforesaid gears and shafts. By means of either hand wheel 23 and the gears 33 the shafts 19 and 20 may be rapidly turned to bring them to an approximate position of adjustment, and then by rotating said gears through the medium of the pinion 35 the shafts may be brought to the accurate degree of adjustment desired. Hence it will be understood that by directly turning the shafts through the medium of one of the hand wheels 23, the drums may be rapidly revolved to bring widely separated portions thereof rapidly into position for use, and that then by turning the pinion 35 the drums may be relatively rotated to the required degree to accurately bring determined portions thereof into position for co-operation in making computations or calculations.

45. Disposed at a point equidistantly between the carrier shafts and the centers of the drums is a transversely extending channelled guide bar 37 suitably fixed to the side plates 3 and provided with fixed bearing members 38 in which are journaled axially aligned right and left hand and right and left threaded adjusting shafts 39 and 40, which shafts are provided at their outer ends with hand wheels 41 and 42, whereby they may be independently or simultaneously turned. Pointers 43 and 44 are carried by the respective shafts 39 and 40, each pointer being secured by a fastening or clamping member 45 to a nut or traveling block 46 having a threaded bore receiving and engaging the threaded surface of the coacting shaft and provided with suitable guide flanges for engagement with the guide surfaces of the guide bar to hold it and the pointer from dislocation. By rotating these shafts

through the medium of the hand wheels 41 and 42 the pointers may be independently or simultaneously adjusted in a direction transversely of the surfaces of the drums, and when simultaneously adjusted may be moved inwardly or outwardly with relation to each other. The pointers consist of longitudinally bowed strips of metal, celluloid or other suitable material, having indicating end portions adapted to project over the surfaces of the drums to point to registering indicia thereon for indicating or calculating action. In addition to their adjustment by rotating the screw shafts, each pointer may be moved along the guide bar by means of its finger piece 45, whereby the carrier nut is slid longitudinally, the shaft revolving in its course of travel.

It is evident from the foregoing description, that the drums may not only be longitudinally moved on their shafts for adjustment to two different working positions on opposite sides of the center of the casing for coaction with the respective pointers 43 or 44, but may also be rotated to bring different portions of their surfaces into reading position. It will also be seen that the pointers are relatively adjustable along the surfaces of the drums when in such different working positions, and that each drum may be locked to its shaft against sliding motion or released so that the shaft may be turned independently thereof, or so that one drum may be turned independently of the other. When the sliding cover of the casing is turned back, the drums may be arranged in position to be conveniently read, and when the cover is closed the working members will be concealed and protected from dust and injury.

The calculating tabulations or indicia may be directly applied to the peripheral faces of the drums, or may be printed or otherwise inscribed upon sheets 47 and 48 respectively secured to the peripheries of the drums 13 and 14. The sheet 47 upon the upper drum has its surface divided by suitable lines into 100 spaces, each 100 cm. long and drawn at an angle so that when the sheet is folded around the drum the spaces will form a spiral 10,000 centimeters long. Numbers from 1,000 to 10,000 are laid off on this spiral at logarithmic distances, beginning at the left. Each space is then divided into 10 parts and each of smaller division ruled into 10 equal parts. (Not shown). Rulings are also made on this sheet at distances proportional to cosines of angles from the 1,000 end or proportional to the sines of angles from the 10,000 end of the spiral. Log. sine or log. cosine is read directly on the sheet. In a similar way this sheet is to be ruled for secants and cosecants of angles. The sheet 48 upon the lower drum 14 is

- similarly ruled, except that the spiral runs in the opposite direction and the graduations, instead of being from left to right, are from right to left. Green lines are ruled on 5 this spiral proportional to the tangents of angles beginning at the 1,000 end or the cotangents beginning at the 10,000 end. This sheet is also intended for verstsines, chords or hyperbolic functions.
- 10 As an example of carrying out a calculation by means of my improved machine, say to multiply 1049 by 86, set the pointer at 1049 on the upper drum, turn the lower drum so that its pointer shows 86, and clamp 15 the two drums to the shafts. The shafts are then rotated by the gear wheels until the second pointer coincided with the 1,000 end of the lower drum. The upper end of this pointer will then indicate the product. To 20 raise a number to a given power multiply its log. (rate on the opposite drum) by the number of the power. To extract roots divide log. by power of the root. The machine is accurate to six places with a fair 25 approximation in the 7th. On the sheet 47, the sines of angles may be given in green ink and the cosines in red ink, while on the sheet 48 the tangents of angles may be given in green ink and the cotangents in red ink.
- 30 I claim:—
1. A calculating device including computing drums movable longitudinally and rotatable with relation to each other, and co-acting pointers adjustable in a direction longitudinally of the drums.
  2. A calculating device comprising a pair of drums rotatably and longitudinally adjustable with relation to each other, adjustable pointers for coaction with the drums, 40 and means for adjusting each drum longitudinally and rotating both drums simultaneously.
  3. A calculating device including a pair of drums, supports for the drums on which they are slidably and rotatably mounted, means for slidably adjusting each drum and locking it to its support, indicators for co-operation with the drums, and means for rotating the drums through their supports.
  - 50 4. A calculating device including a pair of drums, supports for the drums on which they are slidably and rotatably mounted, means for slidably adjusting the drums upon the supports, and means for rotating the drums through the supports, and adjustable indicators for co-operation with said drums.
  5. A calculating device including rotary 55 supports, a pair of drums rotatable and slidable on said supports, means for independently rotating and sliding each drum on its support, means for simultaneously rotating the drum through said supports, and indicators adjustable for co-operation with said drums.
  6. A calculating device including rotatable supports, a pair of drums carried by said supports, gearing between the supports whereby both drums may be simultaneously rotated by rotating one of said supports, and gearing meshing with the aforesaid gearing whereby rotative motion may also be transmitted to the supports and drums.
  7. A calculating device including rotary shafts, a drum slidably and rotatably mounted on each shaft, means for sliding and rotating each drum, means for fixing each drum to its shaft, and means for rotating the shafts in unison.
  8. A calculating device including a pair 80 of parallel rotary shafts, drums slidably and rotatably mounted on said shafts, means for sliding and rotating each drum, means for fixing each drum against rotation, means for rotating the shafts in unison, and a pair of 85 pointers arranged for co-operation with the drums and adjustable in a path parallel with the axes of the drums.
  9. A calculating device including a pair 90 of parallel rotary shafts, drums slidably and rotatably mounted upon the shafts, pointers arranged for co-operation with the drums, and means for adjusting the pointers relatively to each other and longitudinally of the drums.
  10. A calculating device including a pair 95 of parallel rotary shafts, a pair of drums slidably and rotatably mounted on said shafts, duplex indicators arranged for co-operation with the drums, and means whereby said indicators may be simultaneously or independently adjusted longitudinally of the shaft.
  11. A calculating device including a pair 105 of parallel rotary shafts, a pair of drums slidably and rotatably mounted on the respective shafts, means for fixing each drum to its shaft, means upon each drum for independently adjusting the same, means for simultaneously rotating the drums through 110 the shafts, duplex pointers arranged for co-operation with said drums, and means for adjusting said pointers in a direction longitudinally of the drums.
  12. A calculating device including a pair 115 of parallel rotary shafts, a pair of drums slidably and rotatably mounted on the respective shafts, locking means carried by each drum for fixing it to its shaft, means carried by each drum whereby it may be independently adjusted, gearing connecting the shafts for revolving the same in unison, a guideway disposed between and parallel with the shafts, supports arranged to travel 120 in the guideway, duplex pointers carried by said supports, and devices for shifting said supports along said guideway.
  13. A calculating device including a pair 125 of parallel rotary shafts, a pair of drums slidably and rotatably mounted on the re-

spective shafts, adjustable pointers coöperating with the drums, and locking means for fixing each drum to its shaft.

14. A calculating device including a pair of parallel rotary shafts, a pair of drums slidably and rotatably mounted on the respective shafts, adjustable pointers coöperating with the drums, and locking means

carried by each drum for fixing it to its shaft.

In testimony whereof I affix my signature in presence of two witnesses.
